(57) **CLAIM**

The ornamental design for an elastic cloth, as shown and described.

DESCRIPTION

FIG. 1 is a top view of an elastic cloth in an extended state; FIG. 2 is a bottom view of the elastic cloth in the extended state;

FIG. 3 is a rear view of the elastic cloth in the extended state; FIG. 4 is a front view of the elastic cloth in the extended state;

FIG. 5 is a left view of the elastic cloth in the extended state; FIG. 6 is a right view of the elastic cloth in the extended state;

FIG. 7 is a cross-sectional view of the elastic cloth in the extended state taken along line 7-7 in FIG. 1;

FIG. 8 is a cross-sectional view of the elastic cloth in the extended state taken along line 8-8 in FIG. 1;

FIG. 9 is a top view of the elastic cloth of FIG. 1 in a relaxed state;

FIG. 10 is a bottom view of the elastic cloth in the relaxed state;

FIG. 11 is a rear view of the elastic cloth in the relaxed state; FIG. 12 is a front view of the elastic cloth in the relaxed state;

FIG. 13 is a left view of the elastic cloth in the relaxed state; FIG. 14 is a right view of the elastic cloth in the relaxed state;

FIG. 15 is a cross-sectional view of the elastic cloth in the relaxed state taken in the direction of line 15-15 in FIG. 9; FIG. 16 is a cross-sectional view of the elastic cloth in the relaxed state taken in the direction of line 16-16 in FIGS. 9; and,

FIG. 17 is a detail view of the cross-section of the elastic cloth in the extended state taken from line 17-17 in FIG. 8. The broken lines depict the boundaries of the claimed design and form no part thereof. Broken line cross-hatching depicting portions of the elastic cloth between the upper side and the lower side forms no part of the claimed design. The grayscale tone depicts contrasting appearance.
